UNITED STATES PATENT OFFICE.

JOSEPH CONDE, OF PHILADELPHIA, PENNSYLVANIA, ASSIGNOR OF
THREE-FIFTHS TO CHARLES B. HALSALL AND HENRY C. MAR-
SHALL, OF PHILADELPHIA, PENNSYLVANIA.

MACHINE FOR GLAZING TUBES, &c.

SPECIFICATION forming part of Letters Patent No. 727,294, dated May 5, 1903.

Application filed December 8, 1902. Serial No. 134,448. (No model.)

To all whom it may concern:

Be it known that I, JOSEPH CONDE, a citizen of the United States, residing at the city of Philadelphia, in the county of Philadelphia and State of Pennsylvania, have invented a certain new and useful Machine for Glazing Tubes, Vials, and the Like, of which the following is a specification.

One object of the present invention is to provide a machine for glazing the ends of glass tubes, vials, or the like or, in other words, for making such ends smooth and suitable for commercial use.

Another object of the invention is to provide a machine of the character mentioned which shall be automatic in its action and simple, durable, and comparatively inexpensive in its construction.

Another object of the invention is to so glaze the ends of tubes, vials, and the like as that their production shall be rapid, their quality uniform, and their cost trifling.

Other objects of the invention will appear from the following description, as will also its nature, characteristic features, and scope, reference being had to the accompanying drawings, forming part hereof, and in which—

Figure 1 is a top or plan view of a machine embodying features of the invention. Fig. 2 is a side view of the machine, partly in section, taken from the left-hand side in Fig. 1; and Fig. 3 is a sectional view taken substantially centrally of the machine.

Referring to the drawings, 1 is a feed-apron provided, as it were, with notches in which the blanks 2 may be fed through the machine and in which the blanks are capable of a movement of rotation. As shown, this feed-apron consists of a sprocket-chain provided with projecting fingers and adapted to run in gear with the sprocket-wheels 3 and 4. There is imparted to this feed-apron an intermittent motion by means to be hereinafter described and for purposes to be next described. At the sides of the feed-apron and in line with each other are arranged a pusher 5 and a mandrel or plug 6, which is located adjacent to a region of heat created, for example, by the burners 7 and 8, whose heating-flames are di-

rected toward the inner end of the plug. As 50 the blank is carried forward by the feed-apron the latter pauses when the blank is in line with the pusher 5 and the plug 6, and one end of the blank is in range of the flames from the burners 7 and 8, which impinge upon 55 it. At this time the blank may, as shown in the drawings, rest upon rollers *a*, carried by a frame *a'*, and the sets of rollers *a* are so spaced that a time allowance is afforded for the finished end of the blank to cool before 60 the other end is operated upon, as will be understood from the following description. The machine may be adjusted to different diameters of blanks—for example, rollers *a* of appropriate diameter may be substituted. There are presser-wheels 9, which are actuated in a manner to be presently described, and which while the blank is in the position described contact with and rotate it, so that the blank is being rotated while 65 70 one of its ends is being heated, and in this way uniform heating is insured. This generally-stated result is accomplished by the pusher 5 moving inward toward the center of the machine and in that way pushing the 75 blank crosswise of its carrying apron and bringing its end into the heating region. When the end is thus heated, the mandrel or plug 6 advances inward toward the center of the machine and by contacting with and, if 80 desirable, slightly entering the rotating heated end of the blank finishes it. Mechanism for operating the pusher 5 and the plug 6 will be presently described. Provision may be made for moderating the heat from the burners at appropriate times—for example, just before the end of the blank is finished—and for increasing it as the next blank comes into range of its influence, and such means will be described. The presser-wheels 9 are raised, 85 by means to be presently described, to permit of the passage of one blank from under them and of another blank under them, with its end pushed into position by the pusher 5 for exposing it to the heat, whereupon they 90 again descend, so as to rotate the last-mentioned blank. Mechanism for accomplishing this will be described.

The machine shown in the drawings is intended to operate on both ends of a blank, first on one end and then on the other, so that there are, in effect, two sets of duplicate 5 parts, and a description will be given of only one set, as from it the other set will be readily understood.

Intermittent motion may be imparted to the feed-apron 1 by a variety of mechanism. 10 However, a description will be given of the mechanism shown in the drawings for accomplishing that purpose.

Upon the shaft of the sprocket-wheel 4 there is a pinion 10, Fig. 2, adapted to mesh with a mutilated pinion 11, of which the shaft is provided with a toothed wheel 12, which meshes with a toothed wheel 13, fast on the power-shaft 14. The pusher 5 is shown as held up to the working face of a cam 15 by 15 means of a spring, and the plug 6 is similarly held up to the working face of a cam 16. The cams 15 and 16 are secured to counter-shafts 17 and 18. The shaft 18 is driven by the sprocket-gearing 19 from the power-shaft 14, 20 and the shafts 17 and 18 are geared together by the toothed wheels 20. The high parts of 25 the cams 15 and 16 are so set in respect to each other that the pusher 5 is first pushed in toward the center of the machine and afterward the plug 6 is pushed in toward the 30 center of the machine, and they both recede from the center of the machine at practically the same time. The presser-wheels 9 are journaled at the ends of swinging arms 21, pivoted on shafts 22 and 23, which latter are carried by suitable supports. The presser-wheels 35 are rotated by means of sprocket chains and gears from the shafts 22 and 23. The shaft 23 is driven from the shaft of the wheel 11, 40 Fig. 2, which shaft is itself driven in the manner hereinbefore described. The shaft 22 is driven by a sprocket chain and gear 24 from the power-shaft 14. The cams 25 collide with projections 26, carried by pivotal 45 arms 27, which have sliding engagement with yokes 28, connected with the swinging frames 21, so that the high part of the cam 25 collides with the projection 26, turns the arm 27, and thus lifts the swinging frame and 50 brings the presser-wheels 9 out of range of the blanks.

29 represents back-stops for preventing the swinging frames from turning too far downward or from causing the presser-wheels 9 to 55 bear too heavily on the blanks. The faces of these wheels are usually of rubber and operate to rotate the blanks.

The burners 7 and 8 consist of a gas-tube 30, having a row of gas-escape openings along 60 its top and an air-nozzle 31 arranged to play over these gas-openings. The burners are each inclined, and this seems to be productive of excellent results. Furthermore, the burners are mounted on posts which fit into 65 sockets 32, having set-screws, whereby the burners may be elevated and lowered and also directed laterally. Gas enters at 33, the

supply being regulated by a stop-cock, and passes to supply-pipes 34. From these valved connections 35 and 36 lead to the burners. 70 Thus the supply to each burner may be independently adjusted. Air enters under pressure by way of the pipe 37, Fig. 2, and this pipe is provided with a spring-controlled valve 38. It branches and extends to air-pipes 39, located beneath the gas-pipes 34. From the pipes 39 extend valved branch pipes 40 and 41, which communicate with the burners. Thus the supply of air may be properly adjusted for each burner. The pipes 35, 36, 80 40, and 41 may be flexible, so as to permit of adjustments of the burners in the manner described. A projection 42, which revolves with the wheel 13, periodically collides with the valve-stem of the valve 38, and thus serves 85 to temporarily reduce the supply of air at such times as it is not desirable to have the flames play about the end of the plug 6, or, in other words, when there is no blank in position for being heated. While I have described an intermittent reduction in the supply of air, it is clear that the supply of gas or of gas and air may be intermittently reduced similarly.

The bearings which carry the pushers and 95 plugs, as well as the plates or supports which carry the burners, are adjustably connected, as by means of the set-screws and slots 43, so that they can be shifted toward or away from the center of the machine to accommodate 100 blanks of different lengths. The guides 44 are also shown as provided with set-screw and slot adjustments, and while I have described mechanism for imparting the requisite movements in proper time relation to each 105 other of the feed-apron, pushers, plugs, presser-wheels, and heat-supply, still it is obvious that such mechanism in so far as its purpose is to accomplish known mechanical movements can be modified without the exercise of invention. 110

The blanks may be fed to the feed-apron by means of a chute 45 and delivered therefrom into a hopper 46. The feed-apron, or rather its upper or working face, is shown 115 as arranged well above the top 47 of the supporting-table, so that if a blank should be broken there is a space into which it can fall without interfering with the operation of the machine. The plugs or mandrels may be detachable and interchangeable, so that the machine can be adapted to a variety of work. For example, the contour of the plugs may be curved for making the flaring mouth of test-tubes or straight for tube-vials, or the 120 plugs may be flat-ended to make the knobs on medicine-droppers.

In use blanks which we will assume to be lengths cut from a glass tube, and therefore having rough ends, are placed in the chute 125 45 and are taken from it one by one upon the feed-apron and carried toward the left in Fig. 3. Considering one blank, it arrives beneath the right-hand presser-wheels 9 and

in line with the right-hand pusher 5 and plug 6, whereupon the feed-apron pauses. At this time the burners are delivering heating-flames and the pusher pushes one end of the 5 blank into range of the flames. At this time the right-hand presser-wheels descend and as they rotate they turn the blank. This continues until the blank is well heated, when the plug 6 touches its heated end, and thus 10 glazes it. The pusher and plug and presser-wheels then release the blank and the feed-apron proceeds to move while the heat of the burner is modified. By and by this tube which we are considering reaches the glazing 15 apparatus toward the left in Fig. 3 and its opposite end is by that apparatus glazed in the manner described. It will be understood that two blanks are being operated upon at the same time, so that the production of the 20 machine is comparatively large.

It will be obvious to those skilled in the art to which my invention appertains that modifications may be made in detail without departing from the spirit thereof. Hence I do 25 not limit myself to the precise construction and arrangement of parts hereinabove set forth, and illustrated in the accompanying drawings; but,

Having thus described the nature and objects of my invention, what I claim as new, 30 and desire to secure by Letters Patent, is—

1. A machine of the class specified comprising a burner, a feed-apron having an intermittent motion and adapted to feed blanks 35 in respect to the burner, a reciprocating pusher for shifting a blank to bring one of its ends into range of the heat of the burner, a presser-wheel for rotating the blank while it is exposed to the heat, a reciprocating 40 plug or mandrel for working the heated end of the blank, and mechanism substantially as described for operating said parts in substantially the manner set forth.

2. A machine of the class specified comprising a feed-apron having an intermittent 45 motion and arranged to permit of rotation of the blanks which it carries, two sets of rollers upon which the blanks rotate, two sets of burners, two sets of presser-wheels arranged 50 to rotate the blanks while the apron is at rest, two sets of complemental pushers and plugs

or mandrels arranged to operate successively on opposite ends of a blank, and means substantially as described for operating said parts in substantially the manner set forth. 55

3. A machine of the class specified comprising a feed-apron having an intermittent motion, a swinging frame provided with a rotating presser-wheel, a burner, a pusher for shifting the blank into range of heat of the 60 burner, a plug or mandrel and means substantially as described for operating said parts substantially as set forth.

4. A machine of the class specified comprising a rotating presser-wheel, a burner, a 65 pusher for pushing a blank into range of the heat of the burner while it is being rotated by the presser-wheel, a mandrel or plug for glazing the heated end of the rotating blank, means for intermittently feeding blanks into 70 range of the pusher and presser-wheel and plug or mandrel, and mechanism substantially as described for operating said parts.

5. A machine of the class specified comprising means for rotating a blank and positioning it in respect to a burner and a mandrel and a pusher, a pusher for shifting the blank endwise to bring one end of it into the heat of a burner, a burner, a plug or mandrel for glazing the blank, and means for operating 80 said parts, substantially as described.

6. A machine of the class specified comprising burners, a plug or mandrel, and means for rotating a blank and moving it endwise to present its end to the heat of the burners 85 and to the plug or mandrel, substantially as described.

7. A machine of the class specified comprising burners, means for intermittently presenting the rotating ends of blanks opposite 90 the burners, devices arranged to work on one of the ends of the blanks for independently shifting the blanks endwise to move their other ends toward the burners, and devices for automatically regulating the heat of the 95 burners, substantially as described.

In testimony whereof I have hereunto signed my name.

JOSEPH CONDE.

In presence of—

W. J. JACKSON,
K. M. GILLIGAN.
